OPEN-END WRENCH JAWS HAVING THRUST
AND PULL SURFACES OF DIFFERENT
CURVATURE

Fritz Diebold, Geneva, Switzerland

Application March 23, 1953, Serial No. 344,108

Claims priority, application Switzerland
March 31, 1952

3 Claims. (Cl. 81—119)

1

The present invention relates to an open-end wrench of the type in which the active part of the jaws is in the form of a boss, in such a manner that the movement of rotation by the wrench of an object of polygonal cross-section is effected by the coming into contact of said bosses with two opposite faces of the polygonal object.

When these wrenches are constructed of a metal having a predetermined elasticity, for example of steel, or when their active parts are of too small a curvature, it is possible that during too forceful actuation, the wrench jaws will slide over the corners of the polygonal object.

The open-end wrench according to the invention remedies this disadvantage, because the active part of each jaw is of a rounded shape to provide thrust and pull zones, the radius of curvature of the zone of each of said active parts which applies a thrust against one of the faces of the polygonal object, being made greater than that of the zone of each of said parts which applies a pull to the face of the object, opposite the first face.

One form of construction of an open-end wrench according to the invention is shown diagrammatically and by way of example in the accompanying drawing.

The head of said wrench comprises two jaws 1 and 2 of which the active parts 3 and 4 are in the form of rounded bosses.

The bottom of the jaws 1 and 2 is provided with bosses 5 also adapted to come into contact solely with the faces of an object of polygonal cross-section which is engaged between the jaws.

In the drawing, the wrench is shown in the position of actuation, that is to say when it is being stressed while moving a hexagonal object 7 in the direction of the arrow 6.

The active part 3 of the wrench thus applies a push against the corresponding face of the object 7 whilst the active part 4 applies a pull on the face of the object 7 opposite the first face.

As the wrench is capable of rotating the object 7 in either one direction or the other, the parts 3 and 4 are symmetrical and each thereof is provided, on the outside of the jaws, with a zone 8 by which it applies a thrust and on the inside with a zone 9 by which it applies a pull to the object 7.

The zone 8 of each of the parts 3 and 4 by which it applies this thrust is substantially in the form of an arc of a circle of radius R and the zone 9 of each of said parts is also substantially in the form of an arc of a circle. However, the zones 9 have a radius of curvature r which is smaller than R.

2

The curvature of the zones 8 and 9 may naturally have a shape other than that of arcs of a circle. In these cases the radii R and r represent the average radius of curvature of said zones 8 and 9.

In wrenches of this type, of known construction, the active parts of the jaws do not have the particular shape above described. When using such known wrenches, it is found that at a predetermined moment, one of the jaws is held by friction against the corresponding face of the object to be turned, while the other jaw continues to slip. The first jaw cannot slip at this moment against the corresponding face of the object, because the object abuts against the bottom of the recess in the wrench.

When the resilient spacing of the jaws thus reaches a sufficient value, the wrench slips on the object.

20 The wrench described with reference to the drawing enables the above-mentioned disadvantages to be avoided by reason of the selection of the radii of curvature r and R.

Further, the inner surface of the wrench comprised between the two jaws and in particular the bottom of the recess in the head of the wrench is formed in such a manner that, when under stress, the shortest connecting line S' between the active parts 3 and 4 passes practically through the center of the section line of the object 7 which is in contact with the bosses 5 at the bottom of the jaws. Further, the distance a separating one of the bosses 5 from the center point of the line connecting the two parts 3 and 4 is selected larger than half the distance S separating the bosses 3 and 4 when the wrench is in the normal unstressed position (shown in broken lines).

40 Thus, when stressed during actuation of the object 7, the anchoring points of the bosses 3 and 4 with the object 7, and the points of contact of the bosses 5 with the latter, are located practically on a circle of radius a (a is therefore approximately equal to $\frac{1}{2}S'$).

45 It will be understood that not only open-end wrenches with fixed jaws may be constructed in the manner hereinbefore described, but open-end wrenches with adjustable jaws may also be constructed in the same manner.

50 I claim:

1. An open-end wrench for turning objects of polygonal cross-section, said wrench comprising two jaws, each of said jaws having an active part formed by a boss, said bosses coming into contact with two opposite faces of said object of polygonal cross-section when turning same,

said boss of each jaw being of rounded shape to provide a thrust zone and a pull zone, the radius of curvature of the zone of each of said bosses adapted to apply a thrust to one of the faces of said object of polygonal cross-section being greater than that of the zone of each of said bosses adapted to apply a pull on the face of said object of polygonal cross-section located opposite the first mentioned face.

2. An open-end wrench according to claim 1, 10 bosses being provided at the bottom of the space comprised between said jaws, the distance separating said bosses from the middle of a line passing through said active parts of said jaws when stressed being greater than half the distance 15 separating said active parts when the wrench is not stressed.

3. An open-end wrench according to claim 1, the inner surface of the space comprised between said two jaws being so shaped that a line of

shortest distance between said two active parts of the oppositely located jaws passes practically through the center of the portion of said object of polygonal cross-section when the latter is in contact with the bottom of said space formed between the two jaws, and the wrench is being actuated.
